UNITED STATES PATENT OFFICE.

ISIDOR KITSEE, OF PHILADELPHIA, PENNSYLVANIA.

METHOD AND MEANS OF PRODUCING ARTIFICIAL SILK.

1,389,517.

Specification of Letters Patent. Patented Aug. 30, 1921.

Application filed December 20, 1919. Serial No. 346,420.

To all whom it may concern:

Be it known that I, ISIDOR KITSEE, a citizen of the United States, residing at Philadelphia, in the county of Philadelphia and State of Pennsylvania, have invented certain new and useful Improvements in the Method and Means of Producing Artificial Silk, of which the following is a specification.

10 My invention relates to an improvement in producing artificial silk.

Today, the most troublesome operation in the manufacture of artificial silk consists in the production (so called spinning) of 15 the thread out of the individual fibers.

My invention has for one of its objects, to produce the "spinning" automatically without requiring the removal of the individual fibers from the coagulation bath.

20 Today the receptacles containing the dissolved cellulose are stationary and the number of nipples with which each of the containers is provided has no reference to the number of fibers out of which each thread 25 is to be spun.

My invention contemplates, that the receptacle, or at least that part having the nipples attached to it should be revoluble, and that each of the receptacles should have 30 nipples or other means of outflow to form the fibers of a number equal to the number of fibers out of which the thread has to be spun. In accordance with my invention therefore it is contemplated that a series of individual containers should be employed, one container independent of the other container, each container provided with outlets for the fiber, sufficient in number for one thread, these outlets being revoluble. As it is nec- 35

essary for me to show some means, so that persons versed in the art may practice this my invention, I have illustrated in the accompanying drawing some mechanical means to produce the desired result. But 40

45 it has to be expressly stated, that these mechanical means may be altered to suit requirements. In fact, in the practical application on large scale, I have found it convenient to alter some of these means, and as

50 I will make separate applications for these means, I thought it best to illustrate here these means only in broad outlines, so as to present a guide for the production of the device.

In the accompanying drawing:—Figure 55 1 is a vertical sectional view partly in elevation of the device embodying my invention. Fig. 2 is a fragmentary sectional view partly in elevation of the lower portion of the receptacle containing the cellulose solution. Fig. 3 is a bottom view of Fig. 2 illustrating the arrangement of the so called nipples for the discharge of the cellulose solution. Fig. 4 is a section on the line 4—4 of Fig. 1, illustrating the adjustable rollers 60 through which the thread is carried. Fig. 5 is a vertical section through the porous drum upon which the thread is wound.

In these figures, 1 is the receptacle containing the cellulose solution, provided with its 70 removable cover, securely fastened thereto, 2 indicates the lower part thereof, adapted to be revolved by the means 11. The lower part has to be secured to the upper part in a manner, so that no leak is produced 75 through the pressure required for the forcing of the dissolved cellulose. I have here illustrated the container to consist of the stationary part and the revoluble part, for the reason that in some cases the revolving 80 of the whole container, if the same is of very large dimensions, may involve the expenditure of too great an energy; but when the containers are of comparative small dimensions, the whole container with its outlets 85 may be revolved. 3 indicates the outlets in the form of nipples or otherwise and the arrangement of these nipples so that the outlet parts or points may come in close proximity and to one center is clearly illustrated in 90 Fig. 3. I have illustrated these outlets as six in number, as I take it for granted that the thread to be formed has to consist of six individual fibers, but it is obvious that the number of these outlets may vary with the 95 varying number of fibers required for each thread. 4 indicates the individual fiber issuing from the outlets 3, 5 indicates the thread produced out of the individual fibers, here shown through the process of twisting. I deemed it sufficient to produce this thread 100 through the process of twisting, but where it is required the conversion of the individual fibers into one thread can be produced by the process of interlacing or other process 105 of interweaving or spinning. 6 illustrates two adjustable and revoluble rollers provided each with a recess or groove through

which, if so desired the thread may be carried so as to more securely compact the same. 7 is a revoluble drum or cylinder, by preference made of a porous material, such for instance as unglazed pottery-ware or it may consist of a screen like structure of metal or other suitable material, so that the coagulating liquor may be able to attack the thread on both surfaces. This drum or cylinder is here shown as to be revolved and to have a to and fro movement with the aid of means, such for instance as shown at 8. 9 is the container for the coagulating liquid. I am aware that the nature of this liquid varies in different factories, but as my invention may be practised with all suitable coagulating baths it is not necessary for me to give here the chemical constituents of this bath, more especially so as this will form the subject matter of another application. 10 indicates the means, here as part of a pipe to produce the required pressure with the aid of pneumatic devices, but it is obvious that other means such as depend entirely on gravity may be substituted therefor.

Broadly speaking the operation consists as follows:—The operator after having filled the container 1 with the cellulose solution, applies for a short period the pneumatic or other pressure, so as to force out the individual fibers for a length sufficient to carry them to the drum or cylinder. He then twists or otherwise combines the fibers into one thread. He carries this thread through the compression rollers and secures the end to the drum. After this operation is completed, the means 11 and 8 are put in active operation and the pressure at 10 is again applied. The fibers will again issue from the orifices 3, the part 2 of the container will revolve, spinning thereby the individual fibers into one thread, through the compression rollers the thread will be carried downward and through the revolving of the drum or cylinder the thread will be wound on same. In some cases it may be required to change the drum after one layer is completed, in some cases it may be desired to wind one layer on top of the other layer, and for this reason the means 8 will allow a to and fro movement of the drum. In the latter case flanges may be provided at the end of the drum so that the fibers should not roll off.

The nature of the coagulating bath does not form part of this application and the different chemical constituents of the preferred solution will form the subject matter of a separate application.

If desired a suitable dye may be added to the coagulation bath or the cellulose solution may be tinted with said dye.

I have described the method and means, according to which the thread is produced and wound, when still in the coagulating liquor, but if so desired the thread or the in-

dividual fibers may be removed from the liquor at any step before the process is completed.

I have not described here the method and means of increasing the luster of the produced thread, so also have I not described the method and means of winding the thread from the drum or cylinder into hanks ready for market, automatically and without requiring manual labor, as both of these methods will be subject matters of separate applications and as it is my desire to file a general application covering the whole process, beginning at the raw material, embracing all the different steps and ending with the entire finished product I will only state here, that this application will embrace all required details, so that persons versed in the art may readily practise the same.

Having now described my invention, what I claim as new and desire to secure by Letters Patent is:—

1. In the art of producing artificial silk the improvement which consists in exerting a pressure on the produced thread during the time that said thread is carried through the coagulating bath.

2. In the art of producing artificial silk the process which consists in automatically forcing a series of fibers from a suitable solution, bringing these fibers into one thread compressing said thread and winding the same on a suitable support without severing the continuance of the fiber from the source of supply.

3. In the art of producing artificial silk the method of automatic means to spin or otherwise produce one thread out of a series of fibers without breaking the contact of the fibers with the source of supply in combination with automatic means to compress and carry said thread to a predetermined point.

4. In the art of producing artificial silk the method of automatic means to spin or otherwise produce one thread out of a series of fibers without breaking the contact of the fibers with the source of supply in combination with automatic means to compress and carry said thread to a predetermined point and in further combination with means to automatically wind said thread on a suitable support.

5. In a device of the class described a porous support adapted to carry the produced thread of artificial silk.

6. A device of the class described adapted to form out of a series of fibers, one compacted individual thread and to wind the same on a suitable support without necessitating the removal of the thread from the coagulating bath.

7. In the art of producing artificial silk a mechanical unit comprising a reservoir adapted to contain the required cellulose solution, means to force individual fibers out

of said reservoir, means to compact said individual fibers into one individual thread, means to compress said thread and means to wind said thread on a suitable support, said 5 fibers and threads passing through a coagulating bath.

8. In the art of producing artificial silk a mechanical unit adapted to produce and

compact in one continuous operation the required thread of artificial silk without re- 10 moving the same from its source of supply.

In testimony whereof I affix my signature.

ISIDOR KITSEE.
